JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

CAN-END-FEED MECHANISM.

1,349,833.

Specification of Letters Patent. Patented Aug. 17, 1920.

Application filed September 8, 1916. Serial No. 119,063.

To all whom it may concern:

Be it known that I, JAMES A. GRAY, a citizen of the United States, residing at the city and county of San Francisco and State of California, have invented certain new and useful Improvements in Can-End-Feed Mechanism, of which the following is a specification.

The present invention relates to an apparatus for feeding a can end from a supply thereof, and positioning the same relative to a can body.

The object of the invention is to provide an apparatus for the described purpose in which the moving parts are reduced to the least possible number, and in which the movements of said parts are as small as is consistent with practicable operation. To achieve this result I employ a simple form 20 of conveyer mechanism for the can bodies, which advances said bodies, by intermittent movement, in a straight path through the machine, and by means of the novel can end feed mechanism hereinafter described, I 25 remove the lowermost can end from a stack of ends contained within a magazine, and apply the same to a positioned can body.

In order to more fully comprehend the invention, reference should be had to the 30 accompanying sheets of drawings, wherein—

Figure 1 is a side elevation of the machine.

Fig. 2 is a transverse sectional view taken 35 on the line 2—2 of Fig. 1, and viewed in the direction of the arrows.

Fig. 3 is a detailed plan view, enlarged, 40 of the can end feed mechanism, certain parts being broken away for the sake of clearness.

Fig. 4 is a view similar to Fig. 3, the parts being shown in different positions.

Fig. 5 is a detailed vertical sectional view taken on the line 5—5 of Fig. 3, and viewed 45 in the direction of the arrows.

In the drawings, the reference numeral 1 designates a suitably constructed frame, upon which is supported a table 2. A longitudinally disposed drive shaft 3, Fig. 1 of 50 the drawings, is suitably supported in journals 4 carried by the frame 1, and has mounted upon the end thereof a belt pulley 5 for receiving power from an outside source, not shown in the drawings. A muti- 55 lated worm 6 is fixed upon said drive shaft

3, and meshes with a corresponding worm wheel 7, the latter being fixed upon a transverse shaft 8. Said shaft 8 also carries a sprocket 9, on which operates a feed chain 10, supported at its other end by an idler 60 sprocket 11. The upper run of said feed chain 10 operates within a groove 12, Figs. 2 and 3 of the drawings, in the surface of the table 2. A series of spaced lugs or flights 13 are carried by said chains for the 65 purpose of engaging and advancing the can bodies 14 on the table 2, as shown particularly in Fig. 1, and spaced parallel guide rails 15, suitably supported above said table 2, are provided to guide said can bodies in 70 their proper path. Thus, it will readily be understood that a series of said can bodies 14, placed upon the table 2 at its left hand end, as viewed in Fig. 1, by any means not shown in the drawings, will be carried along 75 said table, between the guide rails 15, in a series of intermittent movements, by the feed chain 10, and may be removed from said table at its right hand end, by any suitable device, as, for example, a horizontally 80 rotatable turret indicated at 16 in Fig. 1.

Positioned above the table 2 near its central portion, and supported thereby, is a magazine 17, adapted to contain a stack of can ends 18. Said magazine comprises a 85 lower plate 19, having formed therein an aperture 20 of proper size and shape to permit of the passage therethrough of a can end, and a plurality of vertically disposed guide rods 21 extending upwardly 90 therefrom. Beneath said lower plate 19 is a member 22, which forms the bottom of the magazine, and which has guide members 23 extending laterally therefrom. Said guide members 23 have guide ways 24 95 formed therein, and in said guide ways is carried a reciprocating slide member 25 having a feed plate 26 secured thereto. Said slide member is reciprocated by means of an eccentric 27, Fig. 2 of the drawings, 100 mounted upon the drive shaft 3, the strap 28 thereof being connected, through a bell crank 29 and a link 30, with the slide member 25.

The lower plate 19 of the can and magazine is recessed on its under side, as shown at 31 in Fig. 5 of the drawings, and a plate 32, Figs. 2, 3, 4 and 5, lies within said recess 31 and is adapted for partial rotation therein.

An arm 33, Figs. 3 and 4, extending later- 110

ally from said movable plate 32, through an aperture 34 in the side of the member 19, is connected at 35 with the upper end of a vertical lever 36, the latter being fulcrumed at 37, Fig. 2 of the drawings, and carrying on its lower end a roller 38 adapted to follow a groove 39 formed in a cam member 40, mounted upon the drive shaft 3. Thus by the rotation of said drive shaft and the cam 40 mounted thereon, the movable plate 32, lying within the lower portion 19 of the magazine 17, is oscillated.

The movable plate 32 has formed therein an aperture 41 of a proper size to permit the passage therethrough of a can end. Said plate 32 is retained within the recess 31 of the member 19 by means of a fixed plate 42, secured to said member 19, as shown at 43 in Fig. 2 of the drawings, said fixed plate 42 having formed therein an aperture 42', similar in size and shape to the apertures 20 and 41 of the plates 19 and 32 respectively, but set out of alinement with said aperture 20 of said fixed upper plate 19. Beneath said lower fixed plate 42, and between the plate and the bottom magazine member 22, is a transversely disposed channel 44, Figs. 2, 3 and 5 of the drawings, within which the feed plate 26 is adapted to slide, and through which a can end may be ejected from the magazine by said feed plate.

The stack of can ends 18 within the magazine 17 normally rest upon the projecting edges 45 of the movable plate 32, as shown in Fig. 4 of the drawings, said plate being positioned with its aperture 41 out of alinement with the aperture 20 of the lower magazine member 19. The oscillation of said plate 32 brings its aperture 41 into alinement with the aperture 20 of said magazine member 19, but in this position the aperture 41 of said plate 32 is out of alinement with the aperture 42' in the lower fixed plate 42, as shown in Fig. 3 of the drawings. The stack of can ends therefore drops down until the lowermost can ends 18' rests upon the projecting edges 46, Figs. 3 and 5 of the drawings, of the lower fixed apertured plate 42. Said lowermost can end 18' in this position lies within the aperture 41 of the movable plate 32, the thickness of said plate being the same as that of said can end. The plate 32 is then returned to its first position, as shown in Fig. 4 of the drawings, thereby bringing its aperture 41 into alinement with the aperture 42' in the lower fixed plate 42, and out of alinement with the aperture 20 in the upper fixed member 19. The can end 18', lying within the aperture 41 of said plate 32, thereupon drops through the aperture 42' of the lower fixed plate 42 and rests upon the bottom magazine member 22, within the channel 44, as shown in Fig. 2 of the drawings. At the same time the remainder of the stack of can ends 18

rests upon the projecting edges 45 of the movable plate 32.

The lowermost can end 18' is fed through the channel 44 by the advancing feed plate 26, and permitted to drop onto a can body 14 positioned correctly for the application of said end 18', by the feed chain 10. The can 14, with its end loosely applied thereto, is then carried out of the machine by said feed chain 10.

It will be readily understood by the foregoing, and by reference to the accompanying drawings, that by the properly correlated movements of the feed chain 10 and the can end feed mechanism, each can body 14 is brought to rest in a position to receive a can end through the feed channel 44; and as each can body is so positioned, the lowermost can end 18' of the stack within the magazine 17 is freed therefrom and removed by the reciprocating feed plate 26.

The invention has hereinbefore been described and is herewith illustrated in its preferred form. I do not wish to be construed as limiting myself thereto, however, for the reason that changes may be made in form and construction without in any way affecting the principles of the invention, and I therefore wish to be understood as claiming the invention as broadly as the state of the prior art will permit.

Having thus described my invention, what I claim as new and desire to protect by Letters Patent is:—

1. In a feed mechanism for non-circular can ends, the combination of a holder adapted to contain a stack of can ends and having means for holding the can ends from turning in their own planes, an oscillating member adapted to be turned in a plane parallel with the can ends to a first can end receiving position and then to a second stack-supporting position and having means of non-circular arrangement which in said first position permit the passage of a can end and which in said second position support the stack excepting the lowermost can end, means for oscillating said member alternately to said positions, and a plate below said oscillating member having means which support the stack in said first position of the oscillating member and which permit the passage of the received and turned can end in said second position.

2. In a feed mechanism for non-circular can ends, the combination of a holder adapted to contain a stack of can ends and having means for holding the can ends from turning in their own planes, an oscillating member adapted to be turned in a plane parallel with the can ends to a first can end receiving position and then to a second stack-supporting position and having an aperture of non-circular shape which in said first position permits the passage of a can end, which

member in said second position supports the stack excepting the lowermost can end, said member being adapted to turn a received can end horizontally, means for oscillating said member alternately to said positions, and a plate below said oscillating member having means which support the stack in said first position of the oscillating member and an aperture which permits the passage of the received and turned can end in said second position.

3. In a feed mechanism for non-circular can ends, the combination of a holder adapted to contain a stack of can ends and having means for holding the can ends from turning in their own planes, an oscillating member adapted to be turned in planes parallel with the can ends to a first can end receiving position and then to a second stack-supporting position and having means of non-circular arrangement which in said first position permit the passage of a can end and which in said second position support the stack excepting the lowermost can end, means for oscillating said member alternately to said positions, and a plate below said oscillating member having means which support the stack in said first position of the oscillating member and which permit the passage of the received and turned can end in said second position, a can body carrier, and means for feeding a can end, which has passed down through said bottom plate, to a can on said carrier.

35 4. In a feed mechanism for can ends, the combination of a can end stack holder, a stack-supporting member having a stack-supporting position under said holder and turnable in a plane parallel with the can ends and adapted when turned to another position to receive a can end and to engage and turn the same when said member is returned to its stack-supporting position, means below said member for supporting the stack when said member is in its receiving position, and mechanism for reciprocating said member alternately to said positions.

5. In a feed mechanism for can ends, the combination of a can end stack holder, a stack-supporting member having a stack-supporting position under said holder and turnable in a plane parallel with the can ends and adapted when turned to another position to receive a can end and to engage and turn the same when said member is returned to its stack supporting position, means for supporting the stack when said member is in its receiving position, and mechanism for reciprocating said member alternately to said positions comprising an arm on said member, an oscillating lever and a cam.

6. In a feed mechanism for can ends, the combination of a can end stack holder, a turnable stack-supporting member under said holder adapted to be positioned to sup-

port the stacked can ends and when turned to another position to receive a can end and to engage and turn the same when said member is returned to its stack supporting position, means for supporting the stack when said member is in its receiving position, and mechanism for reciprocating said member alternately to said positions comprising an oscillating lever, a cam and a rotary shaft carrying said cam; an eccentric on said shaft, a second oscillating lever, a link, and a feed slide connected with said link for removing a can end deposited by said member.

7. A can end feed mechanism comprising a holder adapted to contain a stack of non-circular can ends, a stationary member normally forming the bottom support for said stack of can ends, said member having an aperture adapted for the passage therethrough of a can end and positioned out of alignment with the stack of can ends within the holder, a movable member superposed upon said stationary member, said movable member having a non-circular aperture adapted for the passage therethrough of a can end and to engage and turn the same in its own plane, and mechanism for moving the last mentioned member to carry its aperture into alignment successively with said stack of can ends and the aperture of said stationary member, for successively separating the lowermost can end from said stack.

8. A can end feed mechanism comprising a holder adapted to contain a stack of can ends, a stationary member normally forming the bottom support for said stack of can ends, said member having an aperture adapted for the passage therethrough of a can end and positioned out of alignment with the stack of can ends within the holder, an oscillating member superposed upon said stationary member and turnable in a plane parallel with the can ends, said oscillating member having an aperture adapted for the passage therethrough of a can end, mechanism for oscillating said member to carry its aperture into alignment successively with said stack of can ends and the aperture of said stationary member, for successively separating the lowermost can end from said stack, and means for removing said separated lowermost can end from the holder.

9. A can end feed mechanism comprising a holder adapted to contain a stack of can ends, a stationary member normally forming the bottom support for said stack of can ends, said member having an aperture adapted for the passage therethrough of a can end and positioned out of alignment with the stack of can ends within the holder, an oscillating member superposed upon said stationary member and turnable in a plane parallel with the can ends, said oscillating member having an aperture adapted for the

passage therethrough of a can end, mechanism for oscillating said member to carry its aperture into alignment successively with said stack of can ends and the aperture of said stationary member, for successively separating the lowermost can end from said stack, means for removing said separated lowermost can end from the holder and reciprocating devices for placing the same upon a positioned can body.

10. A can end feed mechanism comprising a holder adapted to contain a stack of can ends superposed flatwise on each other, a movable member associated with the lower portion of said holder, said member having an aperture within which the lowermost can end of the stack is adapted to be received, mechanism for moving said member to carry its aperture out of alignment with said stack of can ends and thereby cause it to support said stack, with the exception of said lowermost can end thereof, means for removing said lowermost can end from below the aperture of said member comprising a reciprocating feed slide for placing said can end upon a positioned can body, and devices for positioning said can body in proper timed relation to the movements of said feed slide.

11. A can end feed mechanism comprising a holder adapted to contain a stack of can ends, an oscillating member engaging the can ends laterally and associated with the lower portion of said holder and turning in a plane parallel with the can ends for turning the lowermost can end as described and separating it from said stack, and supporting the remainder of said stack, reciprocating devices for removing the freed lowermost can end from said holder and placing the same upon a positioned can body, conveyer means for positioning said can body for the reception of said can end, and mechanism for operating said oscillating member, said reciprocating devices, and said conveyer means in timed relation.

12. In a machine for feeding non-circular can ends and the like, the combination of a stack holder adapted to contain the can ends superposed flatwise on each other, two supports in line with said stack holder and each adapted to alternately support the stack and permit the passage of a can end along a path in line with said holder, one of said supports having its supporting function while the other of said supports permits said passage of a can end, and means for turning one of said supports relative to the other in a plane parallel with the can ends and around the said path of feeding of the can ends as they leave the stack, the said turning support having means for engaging the can ends laterally to turn the same as described.

13. In a mechanism for feeding non-circular can ends, the combination of a holder

adapted to contain a stack of such can ends and comprising means to hold the same from turning, and alternately acting supports for the stack engageable with opposite portions of the face of a contacting can end, the first support being arranged between the stack holder and the second support, and being turnable relative to said stack holder into position to receive a can end from the stack and permit the latter to engage the second support and into another position to support the stack and to thereby turn the said can end out of engagement with the second support.

14. A can end feed mechanism comprising a holder adapted to contain a stack of non-circular can ends, a fixed plate below said holder having a non-circular aperture out of line and registry with the can ends when the latter are stacked in said holder, a horizontal oscillatory member turnable around the axis of said holder and arranged between said holder and fixed plate and having an aperture adapted to register with such can ends or with the aperture in said fixed plate, and mechanism for moving said member alternately to its said registering positions.

15. In a mechanism for feeding non-circular can ends, the combination of a holder adapted to contain a stack of such can ends and comprising means to hold the same from turning, alternately acting supports for the stack engageable with opposite portions of the face of a contacting can end, the first support being arranged between the stack holder and the second support, and being turnable relative to said stack holder into position to receive a can end from the stack and permit the latter to engage the second support and into another position to support the stack and to thereby turn the said can end out of engagement with the second support, a can carrier, and means for placing the disengaged can ends successively on the cans presented by said carrier.

16. In a mechanism for feeding non-circular can ends, the combination of a stack holder adapted to hold said can ends superposed flatwise on one another and comprising means for preventing the same from turning around the axis of the stack, a support for said can ends turnable relative to said stack holder around said axis and adapted in a first position to engage under opposite portions of the contacting can end and having an aperture which in a second position receives the said can end, the latter acting at such time to support the other can ends in the stack out of the sphere of action of said turnable support, and said aperture corresponding in shape with the can ends so as to engage and turn them successively edgewise around the axis of the stack holder, and a second support ar- 130

ranged at that side of said turnable support which is away from the stack holder, said second support being adapted to engage opposite portions of the can end which is within the turnable support when the latter is in said second position, said can end being removed from said second support when it is turned by the restoration of the turnable support to its first position, and

10 means for actuating said turnable support,

15 17. In a mechanism for feeding non-circular can ends, the combination of a stack holder adapted to hold said can ends superposed flatwise on one another and comprising means for preventing the same from turning around the axis of the stack, an oscillatory support for said can ends turnable relative to said stack holder around said axis and adapted in a first position to engage under diagonally opposite portions of the face of the contacting can end and having an aperture which in a second position receives the said can end, the latter acting at such time to support the other can ends in the stack out of the sphere of action of said oscillatory support, and said aperture corresponding in shape with the can ends so as to engage and turn them successively edgewise around the axis of the stack

20 holder, and a second support arranged at that side of said oscillatory support which is away from the stack holder, said second support being adapted to engage diagonally opposite portions of the face of the can end which is within the oscillatory support when the latter is in said second position, said can end being removed from said second support when it is turned by the restoration of the oscillatory support to its

25 first position, and means for actuating said oscillatory support.

18. In a mechanism for feeding non-circular can ends, the combination of a stack holder adapted to hold said can ends superposed flatwise on one another and comprising means for preventing the same from turning around the axis of the stack, a support for said can ends turnable relative to said stack holder around said axis and adapted in a first position to engage under opposite portions of the contacting can end and having an aperture which in a second position receives the said can end, the latter acting at such time to support the other can ends in the stack out of the sphere of action of said turnable support, and said aperture corresponding in shape with the can ends so

as to engage and turn them successively edgewise around the axis of the stack holder, and a second support arranged at that side of said turnable support which is away from the stack holder, said second support being adapted to engage opposite portions of the can end which is within the turnable support when the latter is in said second position, said can end being removed from said second support when it is turned by the restoration of the turnable support to its first position, means for actuating said turnable support, 70 a can carrier, and means for placing the removed can ends successively on the cans presented by said carrier.

19. In a machine for feeding non-circular can ends, the combination of a stack holder for holding the can ends superposed flatwise on each other and comprising means for holding them from turning in their own planes, means at two different levels under said means for holding the can ends from turning and for alternately supporting the stack by engaging under portions of a lowermost can end, the upper of said supporting means being shaped to engage a can end laterally for turning said can end in its own plane and itself turning into and out of supporting position.

20. In a mechanism for feeding non-circular can ends and the like, the combination of three elements apertured for the passage of the can ends flatwise and arranged along the path of the can ends and constructed to permit successively the passage of the can ends, the first and second elements being constructed to engage the can ends at their sides, the second element being turnable in a plane transverse to the path of the can ends and in a plane parallel with the plane of the can ends to alternately arrest and permit the passage of the can ends, and the third element being constructed to arrest the passage of the can ends when they are otherwise free to pass the first and second elements, and means for turning the second element alternately out of and into can end 105 arresting position.

In testimony whereof I have signed my name to this specification in the presence of two subscribing witnesses.
